Joseph Schaefer, of Hudson City, N. J.,
Associate

The American Lead Pencil Company, of New York, N. Y.

Letters Patent No. 2267-Dated Feb. 3d, 1866.

Design for a Trade Mark.

The schedule referred to in these letters patent and making part of the same
shall, whom it may concern:

Be it known that of Joseph Schaefer, of Hudson
City in the County of Hudson, and State of New Jersey, have invented a
new design for a Trade Mark, to be used on Lead Pencils, and on the
packages or labels for containing the same, and I do hereby declare that
the following is a full, clear and exact description of the same, reference
being had to the accompanying drawings forming a part of this specification,
in which:

Figure 1, represents the design on an enlarged scale.

Figure 2, represents a black lead pencil with the design
printed, embossed or stamped on the end thereof.

This design which may be printed directly upon the
pencils, or upon the packages or wrappers containing them, or upon labels
attached to said wrappers, or to boxes intended to contain the pencils,
represents the figure of an anchor with an entwining or serpent-like cable
passing from the hawser, ring thereof, and entwining the stem of the
anchor previous to the end of the cable passing down through the lower
ring in the lower part of the anchor.

Accompanying this figure and forming a part of the design
is the word Standard, which is intended to be impressed, printed or
otherwise placed upon the pencil, package or label, in about the posi-
tion shown in fig. 2, in relation to the previously described figure.

What I claim as my design and desire to secure by
Letters Patent is—

The design and configuration of the herein described
Trade Mark, consisting of an anchor and cable and the word
Standard, as shown in the annexed drawings.
